UNITED STATES PATENT OFFICE

141,039

DESIGN FOR A HAIR CURLER

Harry Bonat, New York, N. Y., assignor to Samuel Bonat & Bro., New York, N. Y., a copartnership

Application February 22, 1945, Serial No. 118,087

Term of patent 14 years

(Cl. D86—10)

To all whom it may concern:

Be it known that I, Harry Bonat, a citizen of the United States and resident of New York, in the county of New York and State of New York, have invented a new, original, and ornamental Design for a Hair Curler, of which the following is a specification, reference being had to the accompanying drawing, forming a part thereof.

Fig. 1 is a perspective view of a hair curler, showing my new design.

Fig. 2 is a perspective view of the curler shown in Fig. 1, with the handle withdrawn from the curling elements, and with the hair fastener shown broken away for convenience of illustration.

The dominant features of the design reside in the portions shown in full lines.

I claim:

The ornamental design for a hair curler, substantially as shown and described.

HARRY BONAT.
